UNITED STATES PATENT OFFICE

EDGAR F. HATHAWAY, OF WELLESLEY, MASSACHUSETTS, ASSIGNOR TO SHAWMUT ENGINEERING COMPANY, OF DORCHESTER, MASSACHUSETTS, A CORPORATION OF MASSACHUSETTS

YARN CARRIER OR TUBE-FRAME

Application filed July 7, 1928. Serial No. 290,916.

My present invention aims to provide a simplified and improved structure for carrying and presenting tuft yarns for insertion between warps in the course of weaving, being particularly useful in connection with moquette or tuft pile fabric looms, such as Axminster carpet looms. In certain respects the present invention is an improvement upon that disclosed and claimed broadly in the patent to Bixby and Lea 1,590,169, dated June 22, 1926.

In the drawings illustrating certain embodiments of the invention

Fig. 1 is a front elevation of one end portion of a tuft yarn carrier or "tube-frame" and supported yarn spool;

Fig. 2 is a vertical section on the line 2—2 of Fig. 1, a portion of the yarn-end engaging means or grippers of the loom being shown in position about to seize a yarn to draw it into the warp;

Fig. 3 is a bottom plan, with parts broken away, corresponding to Fig. 1;

Fig. 4 is a detail view upon a larger scale, showing a portion of the device as in Fig. 3, the positions of the spacer members or guides being indicated by dotted lines, for the sake of clearness;

Fig. 5 is a detail view in vertical section showing a spacer member or guide and its attaching means;

Figs. 6 to 14 inclusive are respectively vertical sections each corresponding to a portion of Fig. 2 and illustrating certain modifications embodying the invention.

Referring more particularly to the drawings and first to Figs. 1 to 5, the tuft yarn carrier or so-called "tube-frame" comprises the main longitudinal or supporting element 1 or carrier proper, shown as a substantially polygonal tube, bar or frame formed of metal, but which may be otherwise constructed or may be of other material; for example, a wooden bar. Said carrier frame 1 is of a length to receive and support along it one or more tuft yarn spools 2, depending upon the conditions, particularly the width of the work in connection with which the carrier is to be employed. It is provided with any usual or preferred means such as the bearing

member 3 for rotatably supporting the spool pintle 4. Similar spool-supporting means is provided at each end of the carrier, and where a plurality of spools are to be mounted, intermediate means are positioned at the adjacent spool ends for rotatably supporting them thereat. Suitable means such as chain engaging member 5 and the hook latch 6 are also provided at the ends of the carrier, for connecting it with the carrier chain of the loom whereby succeeding carriers with their yarn supplies may be presented in the loom in the customary manner.

For the purposes of description, hereinafter the face or portion of the carrier across which the yarns 7, 7, etc., extend from their spool or spools will be referred to as the front, seen at the left in Fig. 2, and the face or portion of the carrier at an angle thereto and below it, as positioned in Fig. 2, will be termed the bottom.

Extending longitudinally of the carrier and at or adjacent its front face I have provided means for receiving and holding in spaced relation said individual yarns, units or groups of yarn strands 7. In the illustrative embodiment of Figs. 1 to 5 said yarn spacing element, spacer or separator comprises a plate or strip 9 secured to the carrier frame 1 and having a portion projecting laterally beyond the front face of the latter. Said projecting portion of the yarn spacer 9 is provided with a series of properly spaced formations, openings or apertures 10 each to receive and position one yarn or yarn unit 7.

In the Bixby and Lea patent above mentioned there is disclosed a series of yarn spacing apertures having circumferentially continuous or closed walls, necessitating the placing of the yarns by threading them in the direction of their length, whether such lengthwise threading is effected manually or mechanically. In accordance with my present invention, however, the yarn spacing element or spacer 9 at the front of the carrier may be so constructed as to provide for the positioning of the yarns in the receiving formations 10 by a broadside or sidewise threading operation, whereby the entire yarn series or any units thereof may be threaded or re-

threaded, manually or otherwise, either before or during actual weaving operations, novel means also being provided for retaining the yarns in their spaced or threaded relation. It will be understood in this connection that the yarn carrier or "tube-frame" as a whole may be and preferably is originally prepared for use in the loom in the usual manner, that is, by the use of suitable needle-like or other threading mechanism.

Accordingly, as herein illustrated, the yarn-receiving formations or openings 10 of the yarn spacer 9 are provided with lateral and herein front entrance passages 11 formed as by stamping or shearing the material of the front edge of the spacer to provide the deflected or off set portions, teeth or barbs 12. In so forming the latter no stock or substantially no stock is cut away at the locking portions or barbs proper 13 of the teeth 12. Due to this construction a yarn or yarn unit 7 once positioned in its receiving formation or opening 10 can not escape sideways therefrom, unless kinked or bent laterally about the corresponding locking portion 13 of the spacer. The outer portions of the teeth 12 are desirably inclined as indicated at 14 whereby each yarn or yarn unit 7 may readily be entered and guided sideways into its receiving formation or opening 10, but cannot reversely escape therefrom for the reason stated.

In conjunction with said novel side-threading yarn spacer 9 for the carrier or "tube-frame", I preferably provide adjacent yarn-separating and gripper guiding means herein comprising a series of transverse separators, guides or wall-forming members 15. These latter are desirably removably connected with the carrier and associated with the parts thus far described either in groups or individually, being preferably so related to the described yarn spacer as to cooperate therewith in positively retaining the yarns against accidental disengagement from the yarn receiving and spacing formations or openings 10. In accordance with the invention, said yarn-separating gripper guides 15 are positioned and attached through the medium of a longitudinal strip or strips itself or themselves connected to, removably or otherwise, or formed as parts of the carrier bar proper or frame 1.

In the illustrative embodiment of Figs. 1 to 5 said attaching means for the yarn-separating gripper guides 15 comprises a strip or plate 16 extending lengthwise the carrier throughout substantially the full length thereof either as a single member or as a plurality of shorter units. Said attaching strip 16 is positioned flatwise at the bottom of the carrier and herein immediately beneath the yarn spacer 9, the latter and said strip 16 being there secured, preferably removably, by any suitable fastening means such as the screw or bolt 17, see Figs. 2 and 3,

extending through accurately located openings in the adjacent face of the carrier frame 1 and releasably engaging the opposite frame wall as by means of the lock-nut 18. To insure accurate registration of the attaching strip 16 and the yarn spacer 9 with the carrier frame, the edges of the fastener-receiving apertures or recesses in the attaching strip may be upset as indicated at 19, Fig. 2.

The yarn-separating guides 15, as best seen in Figs. 2 and 5, each comprises a preferably metallic blade, strip or the like of a length to extend approximately from the outer edge of the yarn spacer 9 sufficiently toward the rear of the carrier to be engaged with the attaching strip 16 and insure accurate retention of the guide. In the form of the invention as illustrated in Figs. 1 to 5, the attaching strip 16 is formed with a depending flange 20 at its forward portion, which flange is provided with a longitudinal series of formations, slots, notches, perforations or the like 21 generally corresponding in outline to the cross-sectional form of the individual guides 15. The several guides are positioned in and by the corresponding formations 21 and are secured, preferably removably, in such position by suitable means such as the locking bar or pin 22 extending through an opening provided for the purpose in each guide and so located as to bring it into or substantially into contact with the inner face of the flange 20 when the guides are in proper position, thereby preventing their disengagement toward the front of the carrier.

Additional securing means preferably is provided rearwardly of the flange 20. In the form of Figs. 1 to 5 the guides 15 are formed at their inner or rear ends with a tail or nib 23. A lock strip 24 is secured to the rear of the carrier as by the screws 25 tapped into the adjacent wall, riveting or otherwise, said lock strip having a forwardly or inwardly projecting lip 26 notched along its forward edge as at 27 to receive the inner or rear ends of the respective guides 15; see particularly Fig. 3. As best seen in Fig. 2 the tails or nibs 23 of the several guides are held between said lip 26 of the lock strip and the under face of the attaching strip 16. The guides are thus retained against movement in any direction, but may readily be removed, individually or in groups, upon withdrawal of the locking pin 22.

It will be noted by reference to Figs. 1, 3 and particularly Fig. 4, that each guide 15 is so positioned with relation to the adjacent yarn-receiving formation or opening 10 of the spacer 9 that it covers the yarn entrance passage 11 leading to that formation or opening, including particularly the inner end of said passage, so that a portion of the guide overlaps or lies across the exit of each opening 10, as indicated at 28 in Fig. 4.

The described construction and arrangement affords a positive bar to escape of the yarns through the side-threading entrance passages 11, necessitating a further lateral deflection or kinking of any yarn before it could enter the inner end of the corresponding passage 11 in addition to that necessitated by the deflected construction of the yarn spacer teeth or barbs 12. Thus each yarn or 10 yarn unit 7 when once positioned in its receiving formation or opening 10 is both prevented from working out toward or into the exit passage and also from escaping through said exit passage should it work into it in 15 any manner; each yarn or yarn unit is thus positively locked in spaced or threaded position upon the carrier.

The series of yarns or yarn units 7 coming from the spool supply extend through the 20 spacing formations 10 of the spacer 9 and downwardly between two adjacent guides 15. The latter not only function as yarn-separating and guiding elements in conjunction with the spacer 9 but also serve as guides for the 25 yarn engaging means or grippers G of the loom. The flange 20 is located sufficiently rearwardly of the yarn ends to afford proper operating space for the gripper noses, as clearly seen in Fig. 2. Each yarn or yarn 30 unit and its gripper are thus enclosed and guided upon three sides, laterally by the guides 15 and rearwardly by the flange 20. To prevent accidental withdrawal of the yarn 35 ends lengthwise from the formations 10, the latter may be formed with roughened or burred edges or otherwise to engage frictionally with the yarn received by it.

Referring now to the remaining figures of the drawings, there are illustrated certain 40 modifications embodying the general broad combination of the present invention. In considering each of Figures 6 to 14, inclusive, parts not otherwise mentioned may be considered as similar to the corresponding parts 45 as shown in Figs. 1 to 5.

In Fig. 6 the yarn spacer 9a is similar to that of Figs. 1 to 5 but terminates forwardly of the rear wall of the carrier frame 1. The 50 yarn-separating guides 15a are of corresponding length and are formed with projections or tenons 29 at their rear ends. The attaching element or strip 16a is in this instance provided with front and rear depending flanges 20a and 30, respectively, the latter having notches, openings or other 55 formations for the reception of said tenons 29. The portions of the rear end of each guide 15a above or below its tenon abuts the inner face of the rear flange 30 whereby, in 60 conjunction with the locking pin 22a, the guide is locked releasably in position. In this as well as in all succeeding figures the broadside-threading yarn-receiving portion 65 of the spacer is similar to that of the spacer 9, Figs. 1 to 5. It is also noted that in any

form having a tubular or hollow carrier frame the latter may be suitably reinforced interiorly, for example, as disclosed and claimed in my prior Patent 1,545,464, dated July 7, 1925.

Referring to Fig. 7 the yarn spacer or 70 yarn spacing element 9b is herein formed integrally with the carrier frame 1b, comprising a lateral extension of the under wall of the latter. The yarn-separating gripper guides 15b and their attaching element 16b may be 75 the same as in Fig. 6.

In the further embodiment of Fig. 8 the carrier frame 1 is polygonal and tubular as 80 in the form of Figs. 1 to 5 and Fig. 6, but the yarn spacing element 9c is formed integrally with the guide attaching element 16c. The front flange 20c of the latter comprises a doubled strip substantially as illustrated, the yarn spacer 9c being an angular forward extension therefrom. The attaching element or screw 17 is located intermediate the two flanges of the attaching strip 16c as in the 85 previous modifications of Figs. 6 and 7.

In Fig. 9 the yarn spacer 9d and the attaching strip 16d are likewise integrally formed, as in Fig. 8, but the guide engaging portion of the latter is reversed. The horizontal portion of the strip 16d intermediate the flanges 20d and 31, respectively, is at the 90 bottom of the attaching strip and the securing means or bolts 17d are located forwardly of the forward flange 20d.

In the further modification of Fig. 10 the carrier frame 1e is partially open and is 100 formed with integral downward extensions 32, 33, respectively, constituting flanges for receiving and locking the yarn-separating gripper guides 15e similarly as in the previous figures. The yarn spacer 9e is formed 105 with a flange 34 secured to the frame 1e as by the transversely extending bolt or screw 17e.

In Fig. 11 the guide attaching strip 16f and the guides 15f are similar to those of Figs. 6 and 7. The carrier frame 1f in this 110 instance is composed of a plurality of parts, a main part 35 forming three walls and a supplemental part 36 forming a portion of the bottom wall. The two parts are folded together or otherwise interconnected at their 115 adjacent edges as at 37. The yarn spacer 9f is formed as an integral forward extension of said supplemental part 36 of the carrier frame.

In the modification illustrated in Fig. 12 120 the carrier frame is in the form of a wooden bar 1g to the bottom of which is attached, as by wood screws 38, a guide attaching strip 16g which may be similar to that of Figs. 6, 7 and 11, and to the forward portion of 125 which is attached a yarn spacer 9g as by means of a flange 39 and wood screws 40.

According to the further embodiment of Fig. 13 the carrier frame 1h has its forward wall downwardly extended and doubled back 130

upon itself to provide a guide-receiving flange 20*h*, and is bent angularly outwardly to form a yarn spacing element 9*h*. At their rear ends the yarn-separating gripper guides 15*h* engage an inturned portion 41 of the carrier frame, being there held in any suitable manner, as for example, by soldering as indicated at 42.

In the form of Fig. 14 the attaching strip 10 or member 16*i* comprises but a single flange 20*i* similarly as in the form of Figs. 1 to 5 but is formed, as illustrated, integrally with the yarn-separator 9*i*. Each yarn-separating gripper guide 15*i* is provided at its 15 rear end with a head 43 and in this instance is inserted through the flange 20*i* from the rear thereof, being held against rearward displacement by suitable locking means such as the spring clamp 44 held in position upon the carrier frame in any suitable manner as indicated, for example, at 45.

My invention is not limited to the particular illustrative embodiments herein shown and described, its scope being set forth in 25 the following claims.

I claim:

1. A tuft-yarn carrier comprising in combination, a tubular frame, a yarn spacer projecting at the front of the latter and having 30 a longitudinal series of yarn-unit receiving formations formed with front-opening yarn entrances, a series of similarly spaced transversely extending guide members underlying said spacer, attaching means extending lengthwise the carrier and having formations for receiving and supporting said guide members, and means extending through the adjacent wall of the carrier frame and engaging its opposite wall for securing said 35 spacer and said guide-member attaching means to said frame.

2. In a tuft-yarn carrier, a substantially tubular frame having spool-supporting means, a yarn-spacing plate extending 45 lengthwise thereof and having yarn-receiving openings accessible to the yarns through one edge portion of the plate, a longitudinal series of guides for yarn-engaging means of a loom, an elongated strip for supporting 50 said guides in spaced relation, and anchoring means for said plate and said strip, said means extending interiorly of the frame between a pair of its opposed walls.

3. In a tuft-yarn carrier for a loom, the 55 combination with a longitudinal carrier-frame, of a yarn-positioning and separating member secured thereto and comprising a longitudinal strip provided with front-opening formations for the broadside reception 60 of the individual tuft-yarns, a depending flange below said member, and a series of transverse guides mounted in said flange, substantially as described.

4. A yarn-positioning and separating member for a tuft-yarn carrier or frame, em-

bracing a longitudinal plate arranged to project at one face of the carrier or frame and having a series of yarn-receiving and positioning formations, one edge portion of said plate being provided with a series of 70 yarn-spacing teeth each having at one side a barb-like shoulder formed by stamping or shearing said member and deflected out of the main plane of the latter thereby to provide a passage for the broadside entrance 75 of a yarn to the corresponding yarn-receiving and positioning formation.

5. In a carrier for the tuft-yarns of looms, a frame, a series of transverse, parallel barriers having their outer portions projecting 80 at one face of the frame, a recessed attaching strip along the inner portions of said barriers for supporting engagement therewith, and an oppositely-disposed similar recessed strip engaging said barriers outwardly of said first strip.

6. In a carrier for the tuft-yarns of looms, a frame, a series of transverse, parallel, yarn-spacing and gripper-guiding barriers having 90 their outer portions projecting at one face of the frame, and a toothed attaching strip along the inner portions of said barriers for supporting engagement therewith.

7. In a tuft-yarn carrier for a loom, a frame, a longitudinal member comprising front-opening guides for the broadside reception of the yarn units, said guides having deflected portions for positively retaining said 95 yarn units therein, cooperating gripper guiding means, and means for attaching said member to the frame.

8. In a tuft-yarn carrier for a loom, a frame, a structurally continuous longitudinal element at the lower portion of the frame and projecting laterally at the frame front, 105 said element formed with front-opening guides for the broadside reception of the yarn units and with deflected portions for positively retaining said yarn units therein, and means for attaching said element to the 110 frame.

9. In a tuft-yarn carrier or tube-frame for looms, a longitudinal member along said carrier or frame projecting sufficiently at one 115 face thereof to receive and separate the yarn units extending across said face and comprising for said purpose a series of yarn-unit spacing formations each having an entrance passage from the outer portion of said member, said formations having deflected portions for positively retaining the yarn-units therein, and cooperating gripper-guiding means.

10. In a tuft-yarn carrier or tube-frame, a longitudinal member at one face of the carrier or frame for separating the yarns, said member formed to provide a lengthwise series of 125 yarn-receiving formations having entrance passages for broadside reception of the yarns, and having a corresponding series of laterally deflected yarn-retaining projections, and 130

gripper-guiding means associated with said yarn-receiving formations.

11. In a tuft-yarn carrier or tube-frame, a longitudinal structurally continuous member at the lower face of the carrier or frame and projecting frontwardly therefrom for separating the yarns, said member formed with a series of projections adapted to receive the respective yarns between them in a broadside manner, each projection having at one side an integral barb-like yarn-retainer extending substantially across to the next adjacent projection and arranged to facilitate said broadside reception of the yarns.
15. 12. In a tuft-yarn carrier for a loom, in combination with a frame, a structurally continuous substantially rigid longitudinal element at the lower portion of the frame and projecting laterally at the frame front, said element formed with front-opening guides for the broadside reception of the yarn units and with deflected portions for positively retaining said yarn units therein.
13. In a tuft-yarn carrier, in combination with a frame, means thereon to support the yarn supply, a series of transverse yarn-separating and gripper-guiding members at the face of said frame opposite the yarn supply, and a longitudinal strip including two substantially parallel depending flanges provided with spaced formations for receiving and retaining said members in operative position by engagement therewith, said engagement of one of said flanges being at a point between the sides of the frame and intermediate the ends of said members, and another of said flanges engaging said members adjacent their inner ends.
14. In a tuft-yarn carrier, in combination with a frame, means thereon to support the yarn supply, a series of transverse yarn-separating and gripper-guiding members at the face of said frame opposite the yarn supply, a depending flange provided with spaced formations for engaging said members intermediate their ends, said members having enlarged portions at their inner ends, and resilient means upon the frame and urging said enlarged portions and said flange into engagement to retain said members in operative position.

In testimony whereof, I have signed my name to this specification.

EDGAR F. HATHAWAY.
